UNITED STATES PATENT OFFICE

AUGUST KADOW, OF TOLEDO, OHIO, ASSIGNOR OF ONE-HALF TO WILBER OWEN AND CHARLES W. OWEN, BOTH OF TOLEDO, OHIO

FILLING MOLD

Application filed June 19, 1926. Serial No. 117,013.

My invention relates to filling molds, and more particularly to a method and apparatus whereby molds may be filled with such material as molten metal without forming cavities in the resultant casting.

More particularly, my invention relates to filling molds by evacuating the gas therefrom and introducing molten metal under atmospheric pressure.

10 I have found that, when molds are filled with molten metal by means of a substantially uniform vacuum sufficiently high to cause complete filling of the mold, there are apt to be cavities in the resultant casting. This is particularly true where the casting is of considerable size, or has portions which are of considerable length in proportion to their cross-section. I have discovered that these cavities are not formed in the castings when 20 a comparatively low vacuum is used, but that a sufficiently low vacuum to avoid the formation of cavities in the casting will not completely fill the mold where the mold cavity is of considerable height, especially where it has 25 portions comparatively long in proportion to their cross-section.

In my application Serial No. 94,716, filed March 15th, 1926, I have disclosed and claimed a way of overcoming these difficulties 30 by the shape of the intake opening of the mold. By my present invention I avoid these difficulties and completely fill the mold cavity without forming cavities in the resultant casting by using low vacuum upon the start and 35 increasing the vacuum while the mold is being filled, so that a sufficiently high vacuum is formed towards the end of the filling period to completely fill the mold. Further details of the invention will appear as the description 40 proceeds.

In the accompanying drawings forming a part of this specification, Figure 1 is a somewhat diagrammatic elevation of apparatus adapted to carry out my method; Fig. 2 is 45 an elevation of the inside of one-half of the mold shown in Fig. 1; Fig. 3 is an enlarged section on the line 3—3 of Figs. 1 and 2; Figs. 4 and 5 are still greater enlargements upon 50 the same line as Fig. 3, and showing castings in the mold; Fig. 6 is an elevation similar to

Fig. 1 of a somewhat modified form of apparatus, and Fig. 7 is a similar view showing another modification.

In the apparatus shown in Fig. 1, there is a mold consisting of mold halves 10 and 11. The mold is closed by handles 12, but one of which is shown, pivoted at 13 upon mold half 11, and adapted to close against pin 14 on mold half 10. In the construction shown, there is an adjusting screw 15 adapted to cause exact closure of the mold.

The mold halves have ground faces which form substantially air tight connection. At the bottom of the mold there is an inlet 16 through which molten metal may be drawn into the mold cavity 17. Vacuum grooves 18 surround the mold cavity. The face 19 of the mold between the mold cavity and the vacuum grooves is preferably ground slightly so as to form an extremely thin passage 70 between the mold cavity and the vacuum grooves.

Vacuum grooves 18 lead into a recess 20 in the upper end of the mold. A pipe 21, leading from recess 20, is provided with a quick-operating valve 22. Valve 22 is connected by flexible pipe 23 with a needle valve 24. Preferably, needle valve 24 is provided with a dial movable adjacent a pointer 25, so that the exact setting of the valve may be observed. Valve 24 controls the connection between pipe 23 and a casing 26, of any desired size. Casing 26 may be connected, as by means of a pipe 27, with a suitable pump.

The operation of the apparatus thus far described is as follows:

Needle valve 24 is set at a proper opening in a manner which will be described later. The opening through needle valve 24 is comparatively small as compared with the opening through valve 22. Then valve 22 is opened, and immediately thereafter the lower end of the mold is dipped in molten metal. After the mold is filled, valve 22 is closed, and the mold is raised and opened. Thereafter the casting is removed, the mold closed, and the operation repeated.

When valve 22 is open, air rushes in and fills the entire length of pipe 23. This pipe may be of any desired length, but is prefer-

ably long enough to contain a considerable amount of air. When the lower end of the mold is dipped into the molten metal, forming a seal for the mold inlet, evacuation of pipe 23, pipe 21, the vacuum grooves and the 5 mold cavity immediately begins. As soon as the vacuum in the mold cavity is sufficient to cause the metal to rise, it enters the mold through inlet 16. As the metal rises in the 10 mold, the vacuum in the mold cavity approaches more nearly to that in chamber 26, so that the final filling of the mold is due to comparatively high vacuum.

The particular mold shown is adapted to 15 form a battery grid.

My method is particularly advantageous in casting such an article, as the passages of the mold are long in proportion to their cross-section and abound in sharp angles. If a constant low vacuum is used to fill such a mold, 20 the metal solidifies before it reaches the top of the mold, leaving that portion of the mold cavity empty, as indicated in Fig. 3. A similar result occurs if needle valve 24 is opened 25 insufficiently.

If substantially constant high vacuum is used, the resultant casting has cavities or bubbles therein, as indicated in Fig. 5. Not only are the larger portions, such as side bars 30, 29 defective because of bubbles 31, but even the smaller cross-bars 32 are likewise defective because of bubbles 33. A somewhat similar result occurs if needle valve 24 is opened too widely.

If needle valve 24 is properly adjusted, 35 vacuum is built up at such a rate that the mold cavity is completely filled, as indicated in Fig. 4, without the formation of cavities in the casting. Not only the side bars 28 of 40 the grid are completely formed, but each of the small cross-bars 29 is likewise perfectly formed, as indicated in Fig. 4.

Needle valve 24 must be adjusted to give 45 a sufficiently low vacuum on the start to avoid the formation of cavities or bubbles in the casting, while it must be open sufficiently wide to build up the vacuum enough to completely fill the mold. The amount that the valve must be opened varies with the kind of 50 metal, the shape and size of the mold cavity, the temperature of the mold, the degree of vacuum in chest 26, the length and size of pipe 23 and of the vacuum grooves in the mold, and other varying factors. But when 55 the needle valve is set so that a perfect casting results, it may be left unchanged so long as conditions remain constant. When changing conditions render it necessary, the needle valve may be adjusted. Usually there is a 60 sufficient margin of safety, between the point where the mold will be completely filled and the point where imperfect castings will be formed, so that the needle valve needs adjustment but seldom.

65 Valve 22 could be omitted, if desired, but

in that case there would be a constant entrance of air through valve 24, except when the mold was sealed by the metal. When valve 22 is used, vacuum is applied only when necessary.

As indicated above, the amount which valve 70 24 must be opened varies with the length and capacity of pipe 23. If more air is contained in the pipe, the valve must be opened wider to produce the same degree of vacuum in the 75 same length of time.

In the modification shown in Fig. 6, this principle is taken advantage of to obtain accurate adjustment of the desired degree of vacuum. In this modification, a cylindrical 80 air receptacle 34 is interposed between valves 22 and 24. This acts as a reservoir for the air, and increases the amount which valve 24 must be opened to produce a given speed in building up the vacuum during the mold filling operation. Of course, the wider the valve 85 must be opened to produce a given effect, the more it has to be turned in order to materially vary the rate at which the vacuum is built up. Consequently a finer adjustment 90 can be made with a chamber interposed between the regulating valve and the mold than can be obtained with the valve in close proximity to the mold.

In the construction shown, there is a piston 95 35 within cylinder 34, the piston having a stem 36 movable, by means of thumb screw 37 resting on bracket 38, to adjust the piston as desired. It will be apparent that raising the piston in cylinder 34 decreases the amount 100 of air which must be withdrawn to produce a given degree of vacuum, and, therefore, increases the rapidity with which the vacuum is built up in the mold during the filling 105 operation. On the other hand, lowering the piston lessens the rate at which vacuum is built up in the mold. In this way, an even finer adjustment may be obtained than by control of the needle valve.

It will be readily understood that, while 110 the introduction of an air chamber between the regulating valve and the mold increases the accuracy with which adjustment may be made, it also increases the amount of air which must be evacuated to produce a given 115 effect in the mold, and, therefore, an air chamber is desirable only when necessary to secure the desired adjustment. The need of such an interposed air chamber will depend upon the metal being molded, the shape of 120 the casting being formed, and other conditions affecting the necessity of accurate adjustment of the rate of increasing vacuum. Needle valve 24 is capable of making sufficiently fine adjustment for ordinary operations, without the interposition of any air cavity greater than that incident to the use 125 of the connecting pipe 23.

In Fig. 7 another modified form of apparatus is shown. In this view, a cylinder 130

is connected to the vacuum cavity within mold half 11^a by means of a pipe 21^a. Within cylinder 40 there is a piston 41 having a piston rod 42 actuated by a roller 43 running in a cam groove 44 on a cam disc 45 mounted on a shaft 46.

In the operation of this device, metal is drawn into the mold by moving piston 41 to the left, as viewed in Fig. 7, and thus evacuating the mold. It will be readily understood that the degree of vacuum in the mold at any given portion of the operation is dependent upon the rapidity of the movement of piston 41, which in turn is dependent upon the speed of movement of the cam shaft and the shape of the cam groove. The apparatus shown in Fig. 7 is particularly adapted for the making of a great number of castings under constant conditions. Under such circumstances the necessary speed of movement of the piston at different portions of its travel may be ascertained and then apparatus prepared to give it the proper movement. Of course, different cams could be used for different articles, but, where frequent adjustments are necessary, they can be made more easily by controlling the opening of a valve than by controlling the speed of movement of a piston.

30 Further modifications and combinations for effecting substantially the same result in controlling the degree of vacuum within the mold will readily appear to those skilled in the art. For example, an adjustable valve 35 might be interposed between a pump, similar to that shown in Fig. 7, and the mold. The preferred method is to interpose an adjustable valve between a substantially constant source of vacuum and the mold, and regulate 40 the valve in accordance with requirements.

While I have mentioned molten metal as the material to be cast, it will be understood that the method is applicable where the mold is filled with other materials requiring like 45 treatment.

Under some circumstances, the metal might be forced into the mold under pressure, the pressure increasing during the filling of the mold. For example, pressure upon the metal 50 might be exerted by gas, and the pressure of the gas might be built up through a regulatable valve, in a manner similar to that described above for increasing the vacuum within the mold cavity. Pressure and vacuum 55 might be used together, and various other similar combinations, obvious to those skilled in the art, may be made, within the scope of the appended claims.

What I claim is:

60 1. The method of introducing material into a mold by differential pressures upon the material outside the mold and inside the mold, the mold having a cavity of such shape and size that a constant differential pressure sufficient to fill the mold results in cavities

within the casting, which consists in gradually increasing the differential pressure as the mold fills up.

2. The method of introducing material into a mold by differential pressures upon the material outside the mold and inside the mold, the mold having a cavity of such shape and size that a constant differential pressure sufficient to fill the mold results in cavities within the casting, which consists in maintaining a differential pressure during the initial filling of the mold low enough to avoid cavities in the casting, and increasing the differential pressure as the mold fills sufficiently to insure complete filling of the mold.

3. The method of introducing material into a mold, which consists in connecting the mold cavity with a source of material, subjecting the material outside the mold to a greater gaseous pressure than that within the mold, and materially increasing the difference in said pressures between the time when the material starts to enter the mold and the time when the mold cavity is filled.

4. The method of introducing material into a mold having a cavity of such shape and size that filling the mold by a substantially constant difference in pressure upon the filling material outside of the mold and inside of the mold results in cavities in the casting, which consists in connecting the mold cavity with a source of material, subjecting the material outside the mold to a greater gaseous pressure than that within the mold, and governing the difference in said pressures so that the initial filling is at a sufficiently low differential pressure to avoid cavities in the casting and the final filling is at a sufficiently high differential pressure to insure complete filling of the mold.

5. The method of filling a mold, which consists in connecting the mold-inlet with material to be molded and thereafter reducing the gas pressure within the mold progressively while the material is filling the mold cavity.

6. The method of filling a mold, which consists in connecting the mold inlet with material to be cast, thereafter exhausting air gradually from the mold, and governing the rate of exhaustion so that the mold cavity is completely filled without forming cavities in the casting.

7. The method of filling a mold, which consists in forming a seal between the mold cavity and a source of material while the cavity is filled with air at substantially atmospheric pressure, and then gradually exhausting the air from the mold at such a rate that the final filling is under a materially higher vacuum than the initial filling.

8. The method of filling a mold, which consists in connecting the inlet of the mold cavity with a source of material while the cavity is filled with air at substantially at-

mospheric pressure, and exhausting the air from the cavity at a substantially constant rate so adjusted that the degree of vacuum within the mold cavity will materially increase during the time in which it takes the material to fill the mold.

9. The method of filling a mold, which consists in providing an air reservoir in connection with a mold cavity, connecting the mold cavity with a source of material while the air in the cavity and reservoir is at substantially atmospheric pressure, and thereafter exhausting the air from said reservoir and cavity at a predetermined rate.

10. The method of filling a mold, which consists in providing an air reservoir in connection with a mold cavity, connecting the mold cavity with a source of material while the air in the cavity and reservoir is at substantially atmospheric pressure, and thereafter exhausting the air from said reservoir and cavity at a predetermined rate, and adjusting the size of the cavity so that the initial filling of the mold will be at so low a vacuum that cavities are not formed in the casting, and that the final filling will be under a sufficiently high vacuum to completely fill the mold cavity.

11. In apparatus of the character described, a mold, means for causing differential pressure on material outside of the mold and inside of the mold, said means being constructed to gradually and materially increase said differential pressure during the time it takes to fill the mold.

12. In apparatus of the character described, a mold having a cavity therein, means for evacuating air from said cavity, and means for adjusting the rate of evacuation so that the degree of vacuum within the mold will increase materially during the time which it takes to fill the mold.

13. In apparatus of the character described, a mold having a mold cavity, a substantially uniform source of vacuum, connecting means having therein a passageway between said source of vacuum and the mold, an adjustable valve controlling said passageway adjacent said source of vacuum, and a quick-opening valve controlling said passageway adjacent the mold.

14. In apparatus of the character described, a mold having a mold cavity, a substantially constant source of vacuum, connecting means having therein a passageway between said source of vacuum and the mold, an air reservoir interposed in said passageway, and means for adjusting the capacity of said reservoir.

60 In testimony whereof, I have hereunto signed my name to this specification.

AUGUST KADOW.
